UNITED STATES PATENT OFFICE.

LEE C. SHARP, OF PLATTSMOUTH, NEBRASKA, ASSIGNOR TO AMERICAN CAN COMPANY,
OF NEW YORK, N. Y., A CORPORATION OF NEW JERSEY.

CAN.

1,318,809.

Specification of Letters Patent. Patented Oct. 14, 1919.

Application filed September 8, 1917, Serial No. 190,296. Renewed August 9, 1919. Serial No. 316,490.

To all whom it may concern:

Be it known that I, LEE C. SHARP, a citizen of the United States, residing in Platts-
mouth, in the county of Cass and State of
5 Nebraska, have invented a new and useful
Improvement in Cans, of which the following
is a specification.

This invention relates in general to the
construction of metallic cans and has more
10 particular reference to cans of the standard
form usually provided to contain vegetables
and other food products although it will
be manifest that the invention has other and
wider application.

15 A principal object of the invention is the
provision of a can having in effect a seam-
less body having edges of uniform thickness.

In cans constructed for the purpose of
20 packing food prior to my invention it has
been generally the custom to overlap the
interlocking edges in forming a side seam
with the result that there is a double thick-
ness of metal at the body ends and where the
25 heads or can ends are secured in place.

Where leakage has occurred in cans thus
constructed it has generally been at the ends
30 of the side seam and by reason of the excess
thickness of metal there located. This in-
vention has for a purpose the elimination of
this extra thickness through the provision
35 of a body, seamless in effect, presenting a
continuous edge of even thickness for the
receiving of the head or can end.

A further object of the invention is the
35 provision of a can which may be more
cheaply constructed in that it will require
less material to construct the body and will
not require solder in the formation of the
side seam.

40 A still further object of the invention is
the provision of a can which will permit the
heads or closures to be seamed to the body
by a more even action of the seam rolls.

Other objects and advantages of the in-
45 vention will be apparent as it is better un-
derstood from the following description
when considered in connection with the ac-
companying drawing illustrating a preferred
embodiment thereof.

50 On the drawing,

Figure 1 is a perspective view of a can
body with one end crimped thereto and em-
bodying my invention;

Fig. 2 is a section through the sheet iron
55 body sheet;

Fig. 3 shows the same after tinning; and

Fig. 4 is a perspective view of a can with
the head double seamed in position.

This invention contemplates the provision
of a can having a welded side seam brought
60 to substantially the thickness of the stock of
the body. In making the can the black metal
or iron body sheet 9 is bent to tubular form
and the side edges welded in a smooth weld,
as indicated at 10 in Figs. 2 and 3 of the
65 drawing. This is coated internally and ex-
ternally with tin as indicated at 11 so that
in the finished tubular body the seam is com-
pletely hardened and the edges 12 are con-
tinuous and unbroken and of even uniform
70 thickness about the entire periphery. The
edge 12 is flanged to receive a double seamed
cover 13, shown in Fig. 4, which is united in
place by a double seam 14. In Fig. 1 the
lower edge 15 has crimped to it a bottom
75 closure in the crimped seam 16. In both
forms of seams it will be observed no edges
overlap in the seam and since the leaks in
the closed cans have chiefly occurred at the
overlapping edges in the seams the percent-
80 age of leaks is very much less where cans
embodying my invention are used. Indeed
with suitable machinery leaks should be sub-
stantially eliminated.

It is thought that the invention and many
of its attendant advantages will be under-
stood from the foregoing description, and it
will be apparent that various changes may
be made in the form, construction and ar-
rangement of the parts without departing
90 from the spirit and scope of the invention
or sacrificing all of its material advantages,
the form hereinbefore described being merely
a preferred embodiment thereof.

I claim:

1. A new article of manufacture, consist-
ing of a can body constructed of a sheet of
metal bent to bring its side edges in contact,
said edges being united continuously edge
100 to edge in a hermetic seam comprising only
one thickness of metal, and a can end seamed
thereto in a double seam which contains a
uniform thickness of the body metal at all
points of the seam, whereby said seam has
no irregularities or leaks.

2. A new article of manufacture, consist-
ing of a can body constructed of a sheet of
metal bent to bring its side edges in contact,
said edges being united continuously edge
105 to edge in a hermetic seam comprising only

one uniform thickness of metal, the ends of said body being formed with seaming flanges of said uniform thickness, and a can end seamed thereto in a double seam which contains a uniform thickness of the body metal at all points of the seam, whereby said seam has no irregularities or leaks.

3. A new article of manufacture, consisting of a can body constructed of a sheet of metal bent to bring its side edges in contact, said edges being hermetically welded continuously edge to edge in a hermetic seam comprising only one uniform thickness of metal, the ends of said body being formed with seaming flanges of said uniform thickness, and a can end seamed thereto in a double seam which contains a uniform thickness of the body metal at all points of the seam, whereby said seam has no irregularities or leaks.

4. A new article of manufacture, consisting of a can body constructed of a sheet of metal bent to bring its side edges in contact, said edges being hermetically united continuously edge to edge in a hermetic seam comprising only one uniform thickness of metal, the ends of said body being formed with seaming flanges of said uniform thickness, and a can end seamed thereto in a double seam which contains a uniform thickness of the body metal at all points of the seam, whereby said seam has no irregularities or leaks, said body and end having external and internal protective coatings.

Signed in the presence of two subscribing witnesses.

LEE C. SHARP.
